UNITED STATES PATENT OFFICE.

THEODORE SMITH, OF NEW YORK, N. Y.

HANDLE AND METHOD OF MAKING THE SAME.

Application filed July 30, 1925, Serial No. 47,120. Renewed October 25, 1926.

The present invention relates to handles such as form parts of umbrellas, canes, and the like and methods of making the same.

Handles of the type forming parts of umbrellas and canes which embody trimmings or ornamentation, hitherto, have been produced by inlaying in portions thereof materials, usually metal, such as sterling silver. A handle under the usual method has 10 grooves cut therein in certain portions thereof, and strips of metal are fitted into the grooves. The metal strips are then pinned or riveted to the handle portions and are finally filed down flush with the adjacent 15 portions of the handle. This method of hand work is not only expensive, but when the handle which is usually of wood dries out, the pins or rivets become loose and the inlaid strips come off. It follows therefore 20 that the results obtained are impractical and unsatisfactory, and besides, this method of inlaying is done after the handle has been shaped and finished and is usually done by silversmiths.

25 The present method for obtaining an inlaid effect is to cut the handle in sections before it is shaped or finished. Where the inlaid effects are to occur solid pieces of metal of desired thickness are arranged between 30 the several sections produced by the cutting, then all of the sections and metal inserts are doweled or glued or otherwise joined firmly. These steps are carried out while the handle is still in the rough, and as the metal inserts 35 will be of a soft nature such as white metal, the entire handle and metal inserts can be worked down, shaped and finished at one time. The result of the practice mentioned is the production of a strong handle with a 40 trimmed or ornamental appearance of substantial inlaid effect. Costs are reduced to a minimum, and the necessity for skilled artisans is obviated.

45 Other features of the invention will appear from the embodiments of the invention which by way of example are described in the following specification and illustrated in the accompanying drawing, in which:

50 Figure 1 is an elevation of a handle embodying the structural features produced in the practice of the method of the present invention.

55 Fig. 2 is a side elevation partly in section showing the structural features of the handle shown in Fig. 1.

Fig. 3 is an elevation of another type of

handle and embodying a modification of the structural features of the present invention.

Fig. 4 is a view of the end of the handle shown in Fig. 3.

As before stated the production of a handle under the present method is accomplished by cutting the same to produce a preferred number of sections from the handle according to the trimmed or ornamental 65 appearance desired. In Figs. 1 and 2 the handle 10 is shown as being cut to provide a piece 11 and pieces 12. Pieces of metal 13, 14 and 15 are utilized. These pieces of metal are sandwiched or placed respectively between the handle 10 and pieces 11 and 12 as shown most clearly in Fig. 2. In the present instance this is accomplished by the employment of dowel pins 16 which extend 70 through the piece 11 and metal pieces 13 and 14 and the opposite ends thereof are respectively disposed in holes 17 in the handle and holes 18 in the pieces 12. Aside from the use of the dowel pins 16 for joining the several parts together the parts will be treated 75 to an application of glue to thereby more effectively bind the parts to constitute a structural integrality. The pieces 12 will be glued to the metal piece 15 and these three 80 parts may then be joined to complete the 85 handle.

In Figs. 3 and 4 the handle embodies a plurality of pieces 20 which are cut from the handle, and a plurality of metal pieces 21, and a piece 22. The metal pieces 21 extend 90 through transversely, whereas the piece 22 is disposed transversely substantially at a right angle with respect to the pieces 21. The showing in Figures 3 and 4 is made to bring out the fact that any preferred relative disposition of the pieces may be resorted to to obtain different ornamental appearances 95 with inlaid effect.

From the foregoing it will be understood that the method of producing an inlaid effect 100 in handles or similar articles consists first in cutting the article while in the rough or unfinished state in any desired number of sections, then interposing between the sections pieces of comparatively different materials, 105 then joining all of the sections and pieces in any preferred manner, and then finally shaping the work to the desired conformation consistent with the remaining portion of the handle to complete the same.

I claim:

1. The method of making an article of

trim or ornamented inlaid appearance which consists in utilizing an unfinished article, cutting the unfinished article to provide a number of pieces of the article, utilizing pieces of material different from the pieces of the article, joining all of the pieces to the article remnant to obtain a diversified structural unit, and shaping the unit to complete the article.

10 2. The method of making an article of trim or ornamented inlaid appearance which consists in utilizing an unfinished article, cutting the unfinished article, to provide a number of pieces of the article, utilizing pieces of metal, joining all of the pieces to the article remnant to obtain a diversified structural unit, and shaping the unit to complete the article.

15 3. The method of making an article of trim or ornamented inlaid appearance which consists in utilizing an unfinished article, cutting the unfinished article, to provide a

number of pieces of the article, utilizing pieces of material different from the pieces of the article, joining all of the pieces to the article remnant by the use of fastening elements which extend through certain of the pieces and by the use of glue to obtain a diversified structural unit, and shaping the unit to complete the article.

20 4. An article of manufacture comprising a major portion, and minor portions, certain of said minor portions being in the nature of plates arranged and secured between the other minor portions to produce a diversified ornamented appearance.

5. An article of manufacture comprising a major portion, and minor portions, certain of said minor portions being in the nature of plates arranged between the other minor portions to produce a diversified ornamented appearance, and securing means for joining the minor portions to the major portions.

THEODORE SMITH.
